UNITED STATES PATENT OFFICE

2,280,336

PROTECTOR FOR BEER CAN OPENERS

Herman J. Maihack, Jersey City, N. J., assignor of
fifty per cent to George H. Hutaff, Jr., Wilmington, N. C.

Application June 16, 1939, Serial No. 279,554

1 Claim. (Cl. 30—16)

This invention relates to protectors for beer can openers, and the like, and has for one of its objects the production of a simple and efficient means in the nature of a hood or cap which is adapted to be carried by a piercing can opener so as to overhang the pierced opening within the top of a can and prevent the spray of beer or other liquid outwardly through the opening which is being cut in the top of the can.

A further object of this invention is the production of a simple and efficient means for attaching the protector to the well-known type of piercing opener.

Other objects and advantages of the present invention will appear throughout the following specification and claim.

In the drawing:

Figure 1 is a top plan view of the can opener and protector end therefor;

Figure 2 is a side elevational view of the can opener and protector in position upon a can before opening;

Figure 3 is a longitudinal sectional view taken on line 3—3 of Figure 1 with the opener in a position just before piercing the can;

Figure 4 is a view similar to Figure 3 with the opener in a cutting position;

Figure 5 is a perspective view of the protector, the securing sleeve being shown in section;

Figure 6 is a bottom plan view of the protector sleeve, a portion of the can opener being shown;

Figure 7 is a bottom plan view of a modified type of protector.

By referring to the drawing it will be seen that A designates the conventional can opener of the penetrating pointed can-piercing type, as covered by Patent #1,996,550.

My improved protector which is used in conjunction with the can opener just mentioned comprises a sleeve 10 which is slidably mounted upon the shank of the can opener A and this sleeve 10 carries at one end a transverse journal pin 11 and a forwardly extending spring latching tongue 12, which spring latching tongue is provided with a depending lip 13 for fitting into the aperture 14 formed in the conventional can opener A. This spring latching tongue 12 by fitting within the aperture or slot 14 will tend to hold the sleeve 10 in position and against longitudinal sliding movement on the can opener A.

A protector hood 15 which may be of any suitable or desired shape, but preferably of a substantial heart shape to fit snugly over the aper-

ture cut by the piercing end 16 of the can opener A. This hood 15 is preferably of sufficient size to extend well over and beyond the aperture 17 cut in the top 18 of the can. This hood 15 is provided with a pair of rearwardly extending flanges 19 which are provided with arc-shaped slots 20 through which the journal pin 11 extends, the slots 20 being on a sufficient arc and being so formed as to permit a free sliding movement of the journal pin 11 within the slot 20. The inner edges of the flanges 19 are notched as at 21 to fit snugly over the bead 22 of the can as shown clearly in Figures 2 and 3.

In Figure 7, there is shown a modified type of the invention wherein the hood 15a is formed of rubber or other similar material within which flanges 19a are embedded, which flanges are formed similar to the flanges 19 and are connected to a sleeve 10a through the medium of a journal pin 11a similar to the structure previously described.

In operation the can opener A is fastened in a gripping position around the bead or rim 22 and the hood 15 will extend over in an overhanging position beyond the piercing end 16 and the notches 21 will be engaged by the bead 22 of the can. The device will then take the position shown in Figures 2 and 3 and as the handle of the can opener A is moved upwardly the top 18 will be pierced to provide the opening 17 in the can and the hood 15 will lie snugly over the opening 17 completely covering the opening and preventing spray from beer or other liquid contents of the can from spraying outwardly beyond the top of the can.

Having described the invention, what I claim is:

In combination with a piercing can opener having an elongated handle, a protector hood hingedly secured to the can opener near the piercing end thereof and adapted to overhang the piercing end of the can opener and to shield the opening cut in a can by the opener, said hood having a pair of spaced flanges, a journal pin carried by the can opener and slidably engaging the flanges for providing a hinge connection between the hood and the opener, a sleeve slidably mounted upon said elongated handle, said sleeve carrying said journal pin, and a spring tongue carried by the sleeve and adapted to engage the opener for holding the sleeve against longitudinal movement upon the opener in one direction.

HERMAN J. MAIHACK.
